UNITED STATES PATENT OFFICE.

HARRY J. HUFFORD, OF SCRANTON, PENNSYLVANIA.

THREAD CLEANER.

Application filed April 9, 1928. Serial No. 268,500.

The invention aims primarily to provide a new and improved thread cleaner well adapted for use upon a so-called "washboard" tensioning device for thread or yarn passing 5 to a winding spool of a spooling or analogous machine.

In adapting a thread cleaner of the type disclosed in my allowed U. S. application Serial No. 191,149, filed May 13, 1927, to a thread 10 tensioner of the type set forth, it was found that the thread had a tendency to severely cut one of the cleaning blades due to its direction of travel upon leaving said blade and it is another object of the invention to provide 15 new and improved means for mounting a thread guiding roller above this blade to prevent the thread from dragging thereon with undue friction.

The cleaner embodies two thread cleaning 20 blades having opposed edges between which the thread moves, said blades being shaped to form an entrance throat through which the thread enters the space between said edges, and it is a further aim to so shape one of the 25 lugs which support the roller, as to guard this throat and prevent the thread from possibly lashing out of the same. In this connection, a further aim is to so shape this same lug as to assist in initially guiding the thread into the 30 throat.

Yet another aim is to provide a unique bracket for mounting the thread cleaning means upon the tensioner, said bracket embodying a portion which serves to assist in 35 initially guiding the thread into the above-named throat.

A thread tensioning device of the type above mentioned is usually provided with a stop for limiting the outward movement of 40 the usual throw-off wire for the winding spool to which the thread runs from said tensioner. In placing my invention upon the tensioning device, it is necessary to make other provision for performing this function, and it is another 45 aim of the invention to provide the stop on a gate which normally holds the thread guiding roller against removal, said stop serving also as a handle for moving the gate to and from closed position.

50 A still further object of the invention is to provide a construction which is exceptionally simple and inexpensive, yet highly efficient and in every way desirable.

With the foregoing in view, the invention 55 resides in the novel subject matter hereinafter described and claimed, description being ac-

complished by reference to the accompanying drawing.

Fig. 1 is a perspective view of a thread tensioning device and the improved thread 60 cleaner mounted thereon.

Fig. 2 is a top plan view of a number of parts shown in Fig. 1, showing primarily the construction of the thread cleaner.

Figs. 3, 4 and 5 are perspective views of 65 different groups of parts hereinafter described.

In the drawing above briefly described, the well known thread tensioner is shown at T, the body of this tensioner having the usual 70 attaching arm A and the customary horizontal lug L at the upper end of the thread tensioning means. The bracket for mounting the improved cleaner upon the tensioner T embodies a flat horizontal plate 6 to rest upon 75 the lug L, being secured thereto in any desired manner. In the present showing, the usual hinge pin H of the tensioner, passes through an opening in the plate 6 and is provided with a nut N. I have also shown a 80 screw 7 passing through the plate 6 and threaded into the lug L. Preferably integral with the plate 6, is a horizontal arm 8 whose inner portion 9 extends in one direction from said plate, while its outer end 10 projects in a 85 direction substantially at right angles to said first named direction, the plate and arm being preferably in the same plane. The portion of the plate 6 opposite the arm 8 is directed downwardly at 11 to lie against one side of 90 the lug L and is then projected outwardly providing a horizontal thread guide 12 having an edge 13 which is oblique to the direction taken by the arm portion 9.

Secured by rivets 14, or other desired 95 means, to the free end of the arm 8, is a stationary, horizontally disposed, thread cleaning blade 15 having a straight, thread-engaging, inner edge 16. This blade is substantially parallel with the direction in which 100 the arm portion 9 extends and its free end is disposed in horizontally spaced relation with the plate 6.

A U-shaped body B is formed with a slot 17 in its arm-connecting portion 18, through 105 which the blade 15 passes, one arm 19 of said body B, being provided at its inner side with a longitudinal groove 20 receiving the outer edge portion of said blade 15. The other arm 21 of the body B is formed with 110 a longitudinal groove 22 in its inner side, and in this groove, a second thread-cleaning blade

23 is secured, said blade being provided with a straight inner edge 24 in spaced relation with the edge 16 and parallel therewith, to receive the thread as shown in Figs. 1 and 2. 5 At their free ends, the two blades 15—23, are shaped to provide an entrance throat 25 for the thread, and it will be observed from Figs. 1 and 2, that the edge 13 of this thread guide 12, extends substantially to this throat, 10 for the purpose of assisting in initially guiding the thread into the same. The edges 16—24 of the blades extend along lines which are non-parallel with the outer edge of the stationary blade 15, and the entire body B 15 may be shifted longitudinally of this blade, thereby varying the space between the edges 16—24, as occasion may demand. After making such an adjustment, body B is locked to blade 15 by a set screw 26 which is preferably of a key-operated type. 20

After leaving the blade 23, the thread *t* takes a direction away from the edge 24 of said blade, and to prevent the thread from excessively wearing this edge, I provide a 25 horizontal thread-guiding roller 27 which is positioned above the arm 21. The free end of this arm is provided with a lug 28 having a socket 29 receiving one end of the roller 27. The other end of this roller is received 30 in an opening 30 in a second lug 31 formed on the arm-connecting portion 18 of the body B.

It will be observed from Fig. 2, that while the lug 28 is somewhat above the throat 25, 35 it extends across said throat and hence it prevents the thread *t* from possibly lashing out of the same. From this view, it will also be observed that the outer side 32 of the lug 28 curves toward the throat 25 and is more 40 or less co-incident with the curved edge 13 of the guide 12, assisting in initially guiding the thread into said throat and between the cleaning blades.

Not only does the lug 31 provide for the 45 opening 30 to mount one end of the roller 27, but said lug provides a substantial body of metal into which to thread the set screw 26. Moreover, this lug carries a gate 33 which normally closes the outer end of the opening 30 to prevent removal of the roller 27. Preferably, this gate is pivoted to the lug 31 by a screw or the like 34, with sufficient friction to remain in closed position, being readily movable however to open position when 55 it is desired to remove a worn roller 27 and substitute a new one.

Gate 33 is provided with an integral finger 55 which constitutes an operating handle for it and also serves as a stop for limiting the 60 outward movement of the usual throw-off wire W, preventing excessive vibration of this wire and possible action thereof when not necessary.

The construction which has been shown and 65 described, has proven in actual service to be

highly efficient and in every way desirable. This construction may therefore be considered as preferred, with the understanding however, that within the scope of the invention as claimed, variations may be made. 70

I claim:

1. A thread cleaner comprising a horizontal plate for anchorage upon a support, said plate having a rigid arm which projects horizontally therefrom first in one direction and then in a direction substantially at right angles to the first named direction, a thread cleaning blade secured to the free end of said arm and projecting horizontally therefrom into spaced relation with said plate, and a body mounted on said thread cleaning blade and itself having a thread-cleaning blade, the two blades being spaced apart to receive a thread between them. 75

2. A thread cleaner comprising a horizontal plate for anchorage upon a support, said plate having a rigid arm which projects horizontally therefrom first in one direction and then in a direction substantially at right angles to the first named direction, a thread cleaning blade secured to the free end of said arm and projecting horizontally therefrom into spaced relation with said plate, a body mounted on said blade and having a second blade interposed between the same and said plate, the inner edges of the two blades being parallel but shaped to jointly form a thread entrance throat at the outer ends of said blades, the portion of said plate opposite said arm being directed downwardly, then projecting horizontally and having an oblique edge extending substantially to one side of said throat to assist in guiding a thread into the latter. 90

3. A thread cleaner comprising a U-shaped body and thread cleaning blades having opposed edges extending along the arms of said body, the portions of said blades at the free ends of said arms being shaped to form a thread entrance throat into the space between said opposed edges, a lug on the free end of one of said arms extending across said throat to prevent lashing of the thread out of said throat, a second lug at the inner end of said one arm, both of said lugs projecting from the plane in which said arms are disposed, and an elongated thread guiding member extending between and supported by said lugs. 105

4. A structure as specified in claim 3; the first named lug having an outer side slanted toward said throat to assist in guiding a thread into the same. 110

5. A thread cleaner comprising a U-shaped body and thread cleaning blades having opposed edges extending along the arms of said body, the portions of said blades at the free ends of said arms being shaped to form a thread-entrance throat into the space between said opposed edges, a lug on the free end 115

of one of said arms extending across said throat to prevent lashing of the thread out of said throat, a second lug at the inner end of said one arm, both of said lugs projecting 5 from the plane in which said arms are disposed, an elongated thread guiding roller extending between said lugs, the first named lug having a socket receiving one end of said roller, the second lug being formed with an 10 opening receiving the other end of said roller, and a gate mounted on said second lug to normally close the outer end of said opening.

6. A structure as specified in claim 5; said gate having a handle-forming finger projecting 15 beyond the second named lug and adapted to limit the outward movement of a conventional throw-off wire.

7. A body formed with spaced projecting lugs, a thread guiding roller extending between said lugs, one lug having a socket receiving one end of said roller, the other lug 20

being formed with an opening receiving the other end of said roller, and a gate mounted on said other lug and normally closing the outer end of said opening.

25

8. A thread cleaner bracket comprising a horizontal plate for anchorage upon a support, said plate having a rigid arm which projects first in one direction therefrom and then projects in a direction substantially at 30 right angles to the first named direction, said arm being in substantially the same plane with said plate throughout its length, the portion of the plate opposite said arm being directed away from said plane, then projected 35 outwardly in a parallel plane, and having a thread guiding edge oblique to said first named direction.

In testimony whereof I have hereunto affixed my signature.

HARRY J. HUFFORD.
